Primary Examiner — Jae Liang*Assistant Examiner* — Ji Sun Yoon(74) *Attorney, Agent, or Firm* — Tutunjian & Bitetto, P.C.(57) **CLAIM**

The ornamental design for a cap, as shown and described.

DESCRIPTION

FIG. 1 is a top perspective view of a cap.

FIG. 2 is a bottom perspective view of the cap of FIG. 1.

FIG. 3 is a front elevation view of the cap of FIG. 1.

FIG. 4 is a side elevation view of the cap of FIG. 1.

FIG. 5 is a rear elevation view of the cap of FIG. 1.

FIG. 6 is another side elevation view of the cap of FIG. 1.

FIG. 7 is a top plan view of the cap of FIG. 1; and,

FIG. 8 is a bottom plan view of the cap of FIG. 1.

The evenly dotted broken lines in the figures illustrate unclaimed features of the cap and form no part of the claimed design.
